J. H. OSBORNE

CLAMP FOR SLICING MACHINES

Filed Feb. 24, 1922

FIG. 1

FIG. 2

—FIG. 4

INVENTOR.
JOHN H. OSBORNE.

BY

Lockwood Lockwood
ATTORNEYS.

UNITED STATES PATENT OFFICE.

JOHN H. OSBORNE, OF ANDERSON, INDIANA.

CLAMP FOR SLICING MACHINES.

Application filed February 24, 1922. Serial No. 528,329.

To all whom it may concern:

Be it known that I, JOHN H. OSBORNE, a citizen of the United States, and a resident of Anderson, county of Madison, and State 5 of Indiana, have invented certain new and useful Clamps for Slicing Machines; and I do hereby declare that the following is a full, clear, and exact description thereof, reference being had to the accompanying 10 drawings, in which like numerals refer to like parts.

This invention relates to a clamping device for slicing machines and the like wherein it is desired to rigidly secure the article 15 to be sliced to a carriage such that the article to be sliced will be held immovable and together by the clamping action of the securing member.

The chief object of the invention is to provide 20 a suitable clamping construction which may be associated with slicing machines or the like which will accomplish the aforesaid purposes and which will be adjustable to the article to be clamped.

The chief feature of the invention consists 25 in the particular construction of the adjustable support for the clamp and the construction of the clamp per se.

Another feature of the invention consists 30 in pivotally associating the handle with the clamp, whereby the handle may be moved into a second position, if desired, which will not interfere with the movement of the carriage. The handle likewise is associated with the clamp in order to increase 35 the leverage.

The full nature of this invention will be understood from the accompanying drawings and the following description and 40 claims.

In the drawings Fig. 1 is a front view 45 of a portion of the slicing machine and a carriage thereof showing the improved clamp associated therewith and securing a ham to the carriage. Fig. 2 is a top plan view of the aforesaid construction shown in Fig. 1. Fig. 3 is an enlarged sectional view taken on the line 3—3 of Fig. 2 and in the direction of the arrows. Fig. 4 is a cross 50 sectional view taken on the line 4—4 of Fig. 2 and in the direction of the arrows.

In the drawings 10 indicates a portion of the main frame of a slicing machine and said parts 10 are usually stationarily secured, and between said elements of the 55 main frame 10 is slidably supported a car-

riage construction 11 provided with upwardly extending tines 12 and with a pair of slotted standards 13. The slotted standards 13 are joined together at the top by a cross member or tie rod 14, although if desired the standards 13 may be formed integral with the element 14. The standards 13 are slotted as indicated at 15 and the opposite and inwardly positioned faces of said standards are preferably toothed to provide 60 a rack construction 16. All of the aforesaid construction is old in the art to which the invention applies and forms no part of 65 the invention.

The clamp construction herein illustrated as associated with the aforesaid comprises a bar 20 which is arched intermediate its ends, as shown at 21, and is curved outwardly at 22 to provide a ledge. The ledge 22 supports a plurality of tines 23 which are adapted to engage in the article to be sliced, which herein is illustrated as a ham 24. The end portions 25 and 26 of the arched clamping 70 bar 20 are slidably supported in the 75 slots 15 of the standards 14.

The means for adjustably supporting one end of the clamping bar upon a standard 13 comprises a toothed plate 27 suitably secured to said clamping bar by means of a screw bolt 28, said plate having a tooth 29 which is adapted to engage the teeth of the rack 16. Laterally extending stop pin or pins 30 likewise limits longitudinal movement of the bar 20 in the slot standard 13. 80 By the aforesaid means the outer end of the clamping bar 20 is adjustably supported upon the standard. Other suitable means 85 may be substituted for the aforesaid construction without departing from the broad 90 idea of the invention, but the present construction is utilized since it constitutes a 95 duplication of the yieldable locking construction hereinafter to be described.

Upon the projecting end 26, and opposite 100 the end 25 which has been described as adjustably supported in a slotted standard 13, is secured a handle 32. The handle 32 is provided with a tongue 33 which is receivable in a slot 34 formed in the free end of the end 26 of the clamping bar 20. Suitable 105 pivot means, such as that indicated by the numerals 35 and 36 pivotally support said tongue in said slot. The handle 32, therefore, may be positioned as shown by the full 110 lines in Fig. 2 or may be positioned as shown in the dotted lines in said figure. The

last mentioned construction is not only desirable but necessary when the carriage passes the upright portions of the framework 10 in certain types of slicing machines 5 and the like.

From the aforesaid it will be understood that the end 25 of the clamping bar 20 is adjustably positioned upon the supporting upright 13. Pressure is applied through the 10 handle 32 to the other end 26 of the bar, thereby providing for a maximum leverage and suitable means is associated with the clamping bar 20 near the end 26 to lock or latch said bar in the clamping position. 15 Such means comprises a yieldingly mounted locking toothed plate 37 suitably secured by a screw bolt 38 to a plate 39. The toothed plate 37 has a tooth 40 for engaging the teeth of the rack 16. Thus, as pressure is 20 applied to the handle 32 the tooth 40 rides over the teeth 16 of the adjacent standard and retains said clamping bar in the clamping position.

Herein the means for yieldingly supporting the tooth supporting plate 39 is disclosed as providing a releasable construction for the same. Said construction consists of a longitudinally extending slot 41 in the free end 26 and said slot is reduced at 25 42 to provide a seat for the inner end of a guide plunger 43. The outer end of the guide plunger 43 is secured to an angular end 44 of the plate 39. Herein a coil spring 45 is shown concentric with the guide 30 plunger 43 and bears at opposite ends upon the angular portion 44 of the plate 37 and upon the seat formed by the reduction in the slot 41. It will be understood that when pressure is applied to the transverse 35 portion 44 of the plate 39, the spring 45 will be compressed and the plate 39 will be moved from the position shown in Fig. 1 to release the tooth 40 from engagement with the teeth 16, thereby permitting the clamping bar to 40 be released. Said clamping bar may be maintained in the released position by gripping the handle 32 and maintaining the thumb upon the plate 44 into the desired 45 position. Suitable means, such as the screw 50 50 is adapted to limit the outward movement of the plate 44 but permits the toothed plate 39 to be removed from the end 26 of the bar 20 when desired.

The invention claimed is:

55 1. A clamp for a slicing machine or the like, comprising a clamping bar having an arched clamping face and outwardly curved

portion providing a forwardly projecting lower ledge, means associated with both ends of the bar for adjustably supporting the 60 same upon a slicing machine, and tines supported by the forwardly projecting ledge in advance of the plane including said ends.

2. In a slicing machine, the combination 65 of a pair of relatively stationary, slotted and parallel standards having their adjacent faces serrated, and an elongated clamping bar fixedly mounted in said slotted standards and having a transversely extending plate mounted adjacent one end for serration engagement, a similarly positioned and yieldingly mounted, manually releasable, plate at the opposite end, a handle mounted on one projecting end beyond the standard for clamping with great leverage, 70 and a transversely extending member mounted upon the opposite projecting end for preventing the escape of the bar from the standards.

3. In a slicing machine, the combination 80 of a pair of relatively stationary, slotted and parallel standards having their adjacent faces serrated, and an elongated clamping bar fixedly mounted in said slotted standards and having a transversely extending plate mounted adjacent one end for serration engagement upon both sides of the slot, a similarly positioned and yieldingly mounted, manually releasable, plate at the 85 opposite end for serration engagement upon both sides of the slot, and a handle mounted on one projecting end beyond the standard for clamping with great leverage. 90

4. In a slicing machine, the combination 95 of a pair of relatively stationary, slotted and parallel standards having their adjacent faces serrated, and an elongated clamping bar fixedly mounted in said slotted standards and having a transversely extending plate mounted adjacent one end for serration engagement upon both sides of the slot, a similarly positioned and yieldingly mounted, manually releasable, plate at the opposite end for serration engagement upon both sides of the slot, a handle mounted on one 100 projecting end beyond the standard for clamping with great leverage, and a transversely extending member mounted upon the opposite projecting end for preventing the escape of the bar from the standards. 110

In witness whereof, I have hereunto affixed my signature.

JOHN H. OSBORNE,
